UNITED STATES PATENT OFFICE.

JOHN BROWNING, OF ASHAWAY, RHODE ISLAND.

SWINGING HEADLIGHT-BRACKET.

1,332,026.

Specification of Letters Patent. Patented Feb. 24, 1920.

Application filed July 27, 1918. Serial No. 247,029.

To all whom it may concern:

Be it known that I, JOHN BROWNING, a citizen of the United States of America, residing at Ashaway, in the county of Washington and State of Rhode Island, have invented new and useful Improvements in 5 Swinging Headlight-Brackets, of which the following is a specification.

This invention comprehends generally improvements in that class of inventions known as illuminations and more particularly has reference to a swinging head light bracket for trolley cars, locomotives, etc.

It is the primary aim and object of the 10 present invention to provide a device of the above character designed to be operably mounted either on the dash of a trolley car or on the top of a locomotive boiler and capable of being manually operable by the 15 motorman or the engineer for shifting the head light in various positions of angular adjustment so that the rays from the light will be directed in a corresponding direction and enable the motorman or engineer to readily 20 discern objects in advance of the trolley or locomotive.

It is an equally important object of this 25 invention to provide a device of the above mentioned character wherein improved co-operating oscillatory and swinging parts are employed in conjunction with the head light so that upon operation of either or both of 30 the actuating means for the supports the head light will be swung or tilted, or else 35 swung and tilted simultaneously, thus enabling the motorman or engineer to direct the rays of the head light in various directions.

As an additional object, this invention 40 employs the provision of a head light support of the character mentioned wherein improved co-operating means is employed for clamping the head light on the swinging supporting plate, improved means being 45 also employed in conjunction therewith for releasably locking the head light against accidental displacement from the supporting plate.

More particularly, the present invention 50 contemplates the provision of a head light support of the above mentioned character designed so that both the operating or adjusting means for the oscillatory supporting

plate and the swinging supporting plate will be removably locked against actuation. 55

As a further improvement, this invention may be said to reside in the provision of resilient means for co-operating with the actuating or operating means for the swinging and oscillatory supporting plate for normally holding the latter in a substantially stationary position so that the rays from the head light will be directly in advance of the trolley car or locomotive. 60

It is a more specific object of this invention to provide improved means for operably connecting the swinging plate to the oscillatory plate; and to provide improved means for mounting the oscillatory plate in the main support or dash of the trolley car. 65

Other improvements and novel details in the construction and arrangement of the various parts of the apparatus will be brought out more in detail in the description to follow, which for a clear understanding of the 70 invention should be considered in connection with the accompanying drawings forming a part hereof, and wherein is disclosed for the purpose of illustration a convenient and satisfactory embodiment of the invention. 75 It is to be noted in this connection that minor changes in the construction and arrangement of parts may be made without departing from the principle of operation of the various parts. 80

The invention is clearly illustrated in the accompanying drawings, in which:

Figure 1 is a rear elevation of the invention:

Fig. 2 is a side elevation of the device. 90

Fig. 3 is a top plan view thereof;

Fig. 4 is a transverse section partly in elevation and partly broken away and looking toward the outer face of the oscillatory supporting plate. 95

Fig. 5 is a vertical section taken through Fig. 4 showing a part of the connecting rod in elevation.

Fig. 6 is an elevational detail of the connecting rod between the swinging plate and the operating lever therefor. 100

Fig. 7 is an enlarged sectional detail of the means for adjusting the locking means for the connecting rod. 105

Fig. 8 is a perspective detail of the adjusting member of the said locking means.

Fig. 9 is an elevational detail showing an auxiliary operating means for use in conjunction with the operating lever of the swinging plate when the device is mounted 5 on a locomotive.

Fig. 10 is a rear elevational view of the detail shown in Fig. 9.

Fig. 11 is a perspective detail showing the auxiliary operating means employed in 10 conjunction with the main operating levers for the swinging plates when the device is applied on a locomotive.

Similar characters of reference are employed in all of the above described views, 15 to indicate corresponding parts.

Referring now, more particularly, to the accompanying drawings, there is provided a main support 1 which in the present instance represents the dash of a trolley car (not shown) the upper edge of which support 20 near one side is reduced and formed with an arcuate bearing recess 2 in which is mounted a wearing strip 3. An oscillatory supporting plate 4 is now employed and has rigidly 25 secured to the rear face thereof in proximity to the lower edge a carrier 5 the lower edge of which is arranged in an arcuate form and corresponds to the contour of the recess 2. This carrier is mounted on its curved edge 30 with a wear strip 6 which cooperates with the wear strip 3 when the carrier is seated for oscillatory movement within the recess as indicated in the drawings. A retainer 7 is carried by the outer face of the carrier 5 35 and lies over the adjacent face of the support 1 and serves to assure of the retention of the plate 4 against accidental displacement and the lower edge of this retainer is cut in an arcuate form as indicated by the 40 numeral 8 for a purpose that will presently appear.

A swinging supporting plate 9 is now employed and is used in conjunction with the oscillatory plate 4. In operably connecting 45 the plate 9 to the plate 4 a plurality of bars 10 are provided, the respective ends thereof being pivotally connected through the instrumentality of hinges 11 to the adjacent faces of the plates 9 and 4 and coöperate with the 50 bars 10 in supporting and bracing as well as 55 swingingly connecting the plate 9 with respect to the plate 4.

As intimated, improved means have been 55 provided for detachably mounting a head light 12 on the swinging supporting plate 9. In reducing this feature of the invention to practice pairs of opposed bracket arms 13 have their inner angularly bent ends secured 60 to the side edges and rear face of the plate 9 through the instrumentality of fasteners 14 while a lever 15 has its upper end pivotally connected to the outer end of each of the upper bracket arms 13 while the lower end terminates in a handle 16 which is 65 designed for removable engagement with a

notched retaining disk 17 carried by the outer end of each of the lower bracket arms 13. Coöoperating with the bracket arms are opposed clamps 18 designed in a V-shaped form, the vertices of each of which are connected for horizontal movement to the opposite side edges of the plate 9 between the bracket arms 13 through the medium of hinges 19 while the outer ends terminate in flanges 20 designed for engagement with the outer edge of the head light as indicated in Fig. 3. Each clamp is formed with an arcuate cross bar 21 while a bolt 22 is slidably arranged through the adjacent cross bar 21 being prevented from displacement by a nut 23. Suitable resilient means such as coil springs 24 are arranged about the bolts and exert a tension so as to normally hold the clamps extended with respect to the bracket arms 13 and consequently in yielding engagement with the outer portion of the head light. As is apparent these clamps serve to prevent accidental movement of the outer portion of the head light 12 while the inner end is positively supported through the instrumentality of a bracket 25 which is engaged by a hook 26 projecting from the top of the head light. Another bracket 27 is swingingly mounted through the instrumentality of hinges 28 to the upper edge of the plate 9, and in effect serves as a latch for coöperating with the bracket 25 in clamping the hook. A suitable flexible element such as a chain 29 is also connected to the upper edge of the plate 9 and carries a snap hook 30 on its outer end which is designed to be engaged with the inner end of the chain 29 subsequent to the swinging of the chain about the brackets 25 and 27 so as to removably lock the brackets and prevent the accidental displacement of the head light from position.

In order to actuate the swinging supporting plate 9 a connecting rod 31 has its outer end swingingly connected to the rear face 110 of the plate through the instrumentality of a hinge 32 while the opposite portion of the rod is slidably arranged through the slot 33 in the oscillatory plate 4, while the extreme inner end of the connecting rod is pivoted 115 as at 34 to a manually operable actuating lever 35 the lower end of which is in turn pivoted to a bracket 36 carried by the oscillatory plate 4 as indicated in the drawings. A cover plate 37 is formed with a diagonal slot 120 37' and is arranged about the rod 31 and has its flanged edge 38 rigidly secured to the outer face of the oscillatory plate 4 through the instrumentality of fasteners 39 so as to maintain the main portion of the cover plate 125 37 in closely spaced relation to the plate 4 and over the opening or slot 33 while carried by the connecting rod 31 is a flexible washer 40 which slides between the plate 4 and the cover plate 37 during the adjustment of the 130

operating lever 35. This slot, of course, permits of the free movement of the rod 31 when the lever 35 is being adjusted to swing the plate 9. Another cover plate 41 is formed with a circular slot 41' so as to be arranged about the rod 31 and is also mounted on the inner face of the plate 4 and across the opening being arranged in spaced relation to the inner face of the plate. A locking lever 42 is pivotally mounted as at 43 between the cover plate 41 and the plate 4 and is designed to be swung downwardly at times so as to engage a notch 44 in the rod 31 so as to prevent the sliding of the rod. An actuation of the key 45 is carried by the outer end of the lever and has its shank 46 slidably arranged through an arcuate slot 47 in the plate 4 while the inner end terminates in a lug 47' which is disposed within a casing 48 carried on the opposite face of the plate 4 and removably closed by a hinged cover 49. By opening the cover, of course, access is had to the casing to permit of the insertion of a cotter pin 50 through the lug 47' so as to prevent accidental displacement of the lug through the enlarged upper end 51 of the slot 47. It is through the medium of this enlarged portion 51 that the key is inserted through the plate 4 so as to operate in the slot 47. A swinging latch 52 serves to removably hold the cover 49 in a closed position.

With a view toward providing improved resilient means for normally holding the plate 9 in a substantially spaced parallel relation with respect to the plate 4 so that the rays from the head light will be projected directly in advance of the trolley car, coil springs 53 are arranged about the rod 31 and bear at their inner ends against the adjacent cover plates while their outer ends bear against washers 54 held in turn in a substantially stationary position on the rod 31 through the instrumentality of suitable fasteners such as cotter pins 55. A washer 56 is disposed about the rod 31 and interposed between the cover plate 41 and the adjacent spring 53 while connected to the washer is one end of a coil spring 57, the upper end of which is connected as at 58 to the upper edge of the plate 41 and this spring is tensioned so as to coöperate with the springs 53 in facilitating the supporting of the connecting rod and consequently assuring of the maintenance of the plate 9 in spaced parallel relation with respect to the plate 4. For the purpose of actuating the oscillatory plate 4 a lever 59 is pivotally mounted as at 60 on the inner face of the main support or dash 1 at a point near one end. A connecting rod 61 has one end pivotally connected as at 62 to the lower portion of the lever 59 beneath the pivot 60 and has its opposite end secured through the instrumentality of suitable fasteners 63 to the retainer 7. Another connecting rod 64 has one end pivotally connected by means of a pintle 65 to the upper portion of the lever 59 above the pivot 60 while the opposite end is secured by means of suitable fasteners 66 to the rear face of the plate 4. The extreme upper portion of the lever 59 constitutes a handle 67 and it is apparent that upon swinging of the handle in either direction a corresponding movement will be imparted to the plate 4. Suitable resilient means such as a coil spring 68 is now employed and has its respective ends secured to the connecting rod 64 into a block 69 carried on the inner face of the main support 1 beneath the curved edge of the retainer 7. This spring is tensioned so as to normally hold the oscillatory plate in an upright position, yet this tension is overcome upon the actuation of the lever 67 when it is desired to oscillate the plate 4.

Suitable means for locking the plate 4 against movement consists of a catch 70 which is swingingly connected to the retainer and is engaged in any of the spaces 71 between the lugs 72 on the block 69. This construction serves as a substantially segmental rack. A swinging gravity operable hook 73 is connected to the outer end of the catch 70 and is designed for removable engagement with a keeper plate 74 mounted on the upper edge of the retainer 7. When in this position, of course, the plate 4 may be freely actuated. To removably hold the catch 70 between any of the lugs 72 there is resiliently and swingingly mounted a manually operable lever 75 operably connected to the retainer 7 and is designed to be removably engaged with the catch as indicated in Fig. 1.

Suitable means are also employed for actuating the device from the cab of a locomotive when the main support 1 is mounted on top of the boiler and near the front end thereof. In reducing this feature of the invention to practice, reference will be had particularly to Figs. 9, 10 and 11 wherein is disclosed a bracket 76 designed to be secured to the plate 4. This bracket is formed with a right angularly projecting extension 77 which is bifurcated to provide spaced channel shaped arms 78, the latter serving as a supporting guide for a roller 79. This roller is journaled on a pin 80 which projects from a connecting rod 81 near the angularly bent end 82 thereof. A clamp 83 is carried by the outer end of the bent portion 82 of the rod 81 and is detachably engaged with the upper end of the lever 35 while the inner portion of the rod 81 is slidably arranged through a bracket 84 mounted on a suitable support 85 designed in turn to be mounted on the engine cab (not shown). The extreme inner end of this rod 81 is pivoted as at 86 to an auxiliary operating handle lever 87. A

bracket 88 extends laterally from the support 85 and has its upper edge curved and designed to form a segmental rack 89. The lower portion of the lever 87 is pivotally mounted on a bolt 90 which has one end supported in the bracket 88 and the other end supported in a bracket 91 also projecting from the support. A coil spring 92 is disposed about the bolt 90 and bears against the bracket 91 and against the lower hand lever 87, and serves to releasably hold the latter in engagement with any teeth of the rack 89.

The mode of operation of the invention may be reviewed as follows: Assuming that the parts have been assembled in the manner described and as illustrated in the drawings, to swing the head light 12 to the left, it is only necessary to engage the handle lever 35 and shove the latter inwardly, while to swing the plate 9 in the opposite direction, it is only necessary to pull the lever 35 away from the main support 1. To oscillate the plate 4 toward the right, it is only necessary to engage the handle portion 67 of the lever 59 and swing the latter toward the right, and it follows, therefore, that upon swinging the same lever toward the left, the plate 4 will be oscillated toward the left. Inasmuch as the bars 10 serve to normally support the plate 9 on the plate 4, it is apparent that upon the partial rotation or oscillation of the plate 4 the plate 9 will be moved correspondingly. It is also to be appreciated that the oscillatory and shifting movements may be imparted simultaneously to the plates so as to correspondingly position the light 12 in various positions of angular adjustment with respect to the trolley car or locomotive. The spring 68 under ordinary circumstances serves to hold the lever 67 in a neutral position while the springs 53 co-operate with the spring 57 in holding the lever 35 in a neutral position. In other words, these springs hold the plate normally in an inactive position so that the rays from the head light 12 will be projected directly in front of the trolley car. To disconnect the head light, it is only necessary to release the snap from the chain and move the chain from about the brackets 25 and 27 and also lift the bracket 25 from the hook 26. Subsequent to this operation, either one or both of the levers 15 may be engaged and the lower handle portions removed from the innermost notches in the disk 17 and engaged in the outermost notches in these disks so as to consequently compress the spring and assure of the swinging of the clamps 60 away from the outer portion of the head light.

In the use of the invention on locomotives, the oscillating function is unnecessary, except for initially positioning the apparatus 65 so that the headlight may be rocked in a

horizontal plane. Therefore the lever 67 is only used for initially positioning the head light vertically. The arm 35 is then operated to swing the light to direct its rays to the right or to the left by means of the lever 87 which is positioned in the cab and which is operatively connected with the lever by the rod 81 and its attendant parts, as hereinbefore described.

It is believed in view of the foregoing description that a further detailed description of the operation of the invention is entirely unnecessary. Likewise, it is thought that the advantages of the invention will be readily apparent.

As many changes could be made in the above construction and many apparently widely different embodiments of this invention could be made without departing from the scope thereof and it is intended that all matter contained in the above description or shown in the accompanying drawings shall be interpreted as illustrative and not in a limited sense. It is also to be understood that the language used in the following claims is intended to cover all the generic and specific features of the invention herein described and all statements of the scope of the invention which as a matter of language might be said to fall therebetween.

Having thus described this invention, what is claimed as new and desired to be secured by Letters Patent, is:—

1. A headlight bracket of the character described including a pair of supporting plates, one of which is swingingly connected to the other, one of said plates being mounted for oscillatory movement, and independent means for operating the two plates whereby a headlight may have its rays projected in any direction in a spherical zone.

2. A headlight bracket of the character described, including a pair of supporting plates, one of which is swingingly connected to the other, one of said plates being mounted for oscillatory movement, and of manual means operatively connected with each plate, whereby the one may be swung and the other oscillated or the two operated in unison, for the purpose herein specified.

3. A head light bracket of the character described including a pair of supporting plates one of which is mounted for oscillatory movement while the other is swingingly connected to the oscillatory plate, independent manually operable actuating means associated with the plates, and means for detachably holding the head light on the swinging plate.

4. A head light bracket including a main support, a supporting plate mounted for oscillatory movement thereon, another supporting plate, means for swingingly connecting the last mentioned supporting plate to the oscillatory plate, means for detach-

- ably mounting the head light on the swinging plate, an actuating lever connected to the oscillatory plate, a connecting rod slideable through the oscillatory plate and operably connected to the lever and the swinging plate, and manually operable actuating means on the main support and operably connected to the oscillatory plate for actuating the oscillatory plate.
- 10 5. A head light bracket including a main support, a supporting plate mounted for oscillatory movement thereon, another supporting plate, means for swingingly connecting the last mentioned plate to the oscillatory plate, means for detachably connecting the head light to the swinging plate, manually operable actuating means operably mounted on the oscillatory plate and operably connected to the swinging plate so that upon actuation thereof the swinging plate will be actuated, resilient means coöperating with the oscillatory plate and the actuating means for normally holding the swinging plate parallel with the oscillatory plate, manually operable actuating means on the main support and operably connected to the oscillatory plate for actuating the oscillatory plate, and resilient means connected to the last mentioned actuating means and the main support for holding the oscillatory plate in a neutral position.
6. A head light bracket including a main support, a supporting plate mounted for oscillatory movement thereon, another supporting plate, means for swingingly connecting the last mentioned plate to the oscillatory plate, means for detachably connecting the head light to the swinging plate, manually operable actuating means operably mounted on the oscillatory plate and operably connected to the swinging plate so that upon actuation thereof the swinging plate will be actuated, resilient means coöperating with the oscillatory plate and the actuating means for normally holding the swinging plate parallel with the oscillatory plate, manually operable actuating means on the main support and operably connected to the oscillatory plate for actuating the oscillatory plate, and resilient means connected to the last mentioned actuating means and the main support for holding the oscillatory plate in a neutral position, means for removably locking the oscillatory plate against movement, and means for removably locking the swinging plate against movement.
7. A head light bracket of the character described including a pair of supporting plates one of which is mounted for oscillatory movement while the other is swingingly connected to the oscillatory plate, cooperative head light supporting brackets on the swinging plate, means for removably holding the head light against displacement, manually operable clamping means on the
- swinging plate and engageable with the head light for assuring of the proper positioning of the head light on the plate, manually operable actuable means connected to the oscillatory plate, and manually operable actuable means connected to the swinging plate.
8. A head light bracket of the character described including a main support, a supporting plate mounted for oscillatory movement thereon, another supporting plate, means for swingingly connecting the last mentioned plate to the oscillatory plate, means for detachably connecting the head light to the swinging plate, an actuating lever connected to the oscillatory plate, a connecting rod slideable through the oscillatory plate and operably connected to the lever and the swinging plate, resilient means disposed about the rod and coöperating with the oscillatory plate for removably holding the swinging plate in a neutral position, means mounted on the oscillatory plate for removably locking the connecting rod against movement, and manually operably actuable means on the main support and operably connected to the oscillatory plate for actuating the oscillatory plate.
9. A head light bracket of the character described including a pair of supporting plates one of which is mounted for oscillatory movement while the other is swingingly connected to the oscillatory plate, means for detachably holding the head light on the swinging plate, the oscillatory plate being formed with an opening, cover plates mounted on opposite sides of the oscillatory plate and in spaced relation thereto for covering the opening, each of the cover plates being formed with slots, an actuating lever swingingly mounted on the oscillatory plate, a connecting rod connected to the lever and slideable through the slots in the cover plates and the opening in the oscillatory plate and operably connected to the swinging plate, the rod being formed with a notch, a locking lever pivotally mounted between one of the cover plates and the oscillatory plate being removably engageable with the notch in the rod for holding the rod in a locked position, resilient means for normally holding the swinging plate in parallel relation to the oscillatory plate, and manually operable actuable means for operating the oscillatory plate.
10. A head light bracket of the character described including a main support, a pair of supporting plates one of which is mounted for oscillatory movement on the main support while the other is swingingly connected to the oscillatory plate, means for detachably holding the head light on the swinging plate, the oscillatory plate being formed with an opening, cover plates secured on opposite sides of the oscillatory plate.

plate in closely spaced relation thereto and covering the opening in the oscillatory plate, each of the cover plates being formed with slots, an operating lever pivotally mounted 6 on the oscillatory plate, a connecting rod formed with a notch and slidably mounted through the slots in the cover plates and the opening in the oscillatory plate and having its respective ends operably connected to the 10 swinging plate and to the operating lever, a locking lever pivotally mounted between one of the cover plates and the oscillatory plate and removably engageable with the notch in the rod for holding the latter against movement, a washer disposed about the rod, a coil spring connected to the oscillatory plate and to the washer for facilitating the supporting of the rod, other coil springs disposed about the rod and exerting tension so as to normally 20 hold the swinging plates parallel with the oscillatory plate, another lever operably mounted on the main support, connecting rods between the last mentioned lever and the oscillatory plate whereby upon actuation 25 of the last mentioned lever the oscillatory plate will be correspondingly operated.

11. A device of the character described including a main support formed with an ar-

cuate bearing recess, a supporting plate, an arcuate carrier mounted thereon and seated 30 for oscillatory movement in the recess, a retainer connected to the carrier for preventing accidental displacement of the plate from the main support, a swinging supporting plate operably connected to the oscillatory plate, means for detachably holding the head light on the swinging plate, manually operable means on the oscillatory plate and connected to the swinging plate for actuating the swinging plate, manually operable 35 means on the main support and connected to the oscillatory plate for actuating the oscillatory plate, a block carried by the main support in proximity to the retainer, a plurality of lugs on the block and forming a 40 substantial rack, a catch swingingly mounted on the retainer and engageable between any of the lugs, a pivotally mounted spring tensioned lever for removably holding the catch in a locked position, co-operative means 45 for retaining the catch in an inactive position, and means for removably locking the manually operable means for the swinging plate against movement.

In testimony whereof I affix my signature. 55
JOHN BROWNING.
